(57) **CLAIM**

The ornamental design for a wall lamp, as shown and described.

DESCRIPTION

FIG. 1 is a front, top and right perspective view of the wall lamp showing my new design;

FIG. 2 is a back, bottom and left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view, of framed portion 9, of FIG.1, thereof; and,

FIG. 10 is an enlarged view, of framed portion 10, of FIG.2, thereof.

The broken lines throughout the drawing figures depict portions of the wall lamp that form no part of the claimed design.

The dot-dash broken lines depict the boundaries of the FIGS. 1, 2, 9 and 10 enlargement that forms no part of the claimed design.
